UNITED STATES PATENT OFFICE.

JAMES R. BRYANT, OF CRAWFORDSVILLE, INDIANA.

DESIGN FOR A CREST-TILE.

SPECIFICATION forming part of Design No. 25,052, dated January 14, 1896.

Application filed December 7, 1895. Serial No. 571,441. Term of patent 7 years.

To all whom it may concern:

Be it known that I, JAMES R. BRYANT, a citizen of the United States, residing at Crawfordsville, in the county of Montgomery and State of Indiana, have invented a new and original Design for a Crest-Tile, of which the following is a specification.

This invention relates to a new and original design for a crest-tile, and it has for its object to provide a design of this character that shall be both useful and ornamental.

The leading feature of the design resides in a crest-tile provided in its main body portion with a longitudinal series of multifoil figures and a pair of vertically-aligned circular and star-shaped figures alternating with the multifoil figures.

A minor feature of the design resides in a cylindrical-shaped figure arranged longitudinally at the upper edge of the main vertical body portion of the crest-tile.

In the drawings, Figure 1 is a side elevation of a portion of a crest-tile embodying the herein-described design. Fig. 2 is a transverse sectional view thereof.

Referring to the accompanying drawings, 1 designates the main vertical body portion of a crest-tile provided at its lower edge with an inverted-V-shaped base portion 2 and at its upper edge with a longitudinal cylindrically-shaped figure 3.

The vertical body portion 1 of the tile is provided with a longitudinal series of multifoil figures 4 and a pair of vertically-aligned circular and star-shaped figures 5 and 6, respectively, alternating with the said multifoil figures 4.

What I claim is—

The design for a crest-tile herein shown and described.

In testimony that I claim the foregoing as my own I have hereto affixed my signature in the presence of two witnesses.

JAMES R. BRYANT.
